(57) **CLAIM**

The ornamental design for a wedge based directed LED array, as shown and described.

DESCRIPTION

FIG. 1 is a front perspective view showing the wedge based directed LED array;

FIG. 2 is a front elevational view of the wedge based directed LED array in accordance with the present invention;

FIG. 3 is a top plan view of the wedge based directed LED array;

FIG. 4 is a side elevational view of the wedge based directed LED array, with an opposite side elevational view being a mirror image; and,

FIG. 5 is a back view of the wedge based directed LED array. The broken lines in the drawings represent unclaimed environmental subject matter and forms no part of the claimed design.
